(57) **CLAIM**

The ornamental design for a foot file, as shown and described.

DESCRIPTION

FIG. 1 is a top, front, right side perspective view of a foot file according to our new design;

FIG. 2 is an enlarged front elevation view thereof;

FIG. 3 is an enlarged rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash broken lines represent boundaries of the claimed design and form no part of the claimed design. All other broken lines represent portions of the foot file that form no part of the claimed design.
